US00D886612S

(12) **United States Design Patent** (10) **Patent No.:** **US D886,612 S**
(45) **Date of Patent:** **** Jun. 9, 2020**

(54) **BOTTLE**

(71) Applicant: **PepsiCo, Inc.**, Purchase, NY (US)

(72) Inventors: **Jorge Manuel Maquita Nakano**,
Distrito Federal (MX); **Lori Evans**
Bartman, Sylvania, OH (US)

(73) Assignee: **PepsiCo, Inc.**, Purchase, NY (US)

(**) Term: **15 Years**

(21) Appl. No.: **29/698,827**

(22) Filed: **Jul. 19, 2019**

Related U.S. Application Data

(63) Continuation of application No. 29/675,572, filed on Jan. 3, 2019, now Pat. No. Des. 857,510, which is a continuation of application No. 29/595,046, filed on Feb. 24, 2017, now Pat. No. Des. 840,234, which is a continuation of application No. 29/537,876, filed on Aug. 28, 2015, now Pat. No. Des. 782,910.

(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

1 Claim, 7 Drawing Sheets
